[57] CLAIM

The ornamental design for a telephone set, as shown and described.

DESCRIPTION

FIG. 1 is a top, front and right-side perspective view of a telephone set showing my new design;

FIG. 2 is a top, front, and right-side perspective view thereof, shown with handset removed from base;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The telephone cord shown in part by means of dot-dash lines for convenience of illustration throughout the views is continuous throughout.
